United States Patent

Des. 235,286
Patented June 10, 1975

235,286

CHAIR

Arnold C. Martinelli, Lake Shore Drive,
Rawdon, Quebec, Canada

Filed July 12, 1973, Ser. No. 378,612

Term of patent 14 years

Int. Cl. D6—01

U.S. Cl. D6—56

FIG. 2.

FIG. 1.

FIG. 2.

FIG. 3.

FIG. 1 is a perspective view of a chair showing my new design:

FIG. 2 is a side elevational view thereof:

FIG. 3 is a perspective view of a chair showing a modified form of my design:

FIG. 4 is a side elevational view of the chair of FIG. 3.

A web extends downwardly from the rearward end of the seat to the forward end of the base, the web constituting an extension of the chair back.

I claim:

The ornamental design for a chair, as shown and described.
